W. E. LENA

ELASTIC CUFF LINK

Filed Sept. 10, 1925

INVENTOR

Walter E. Lena

BY

H. G. Manning

ATTORNEY

UNITED STATES PATENT OFFICE.

WALTER E. LENA, OF WATERBURY, CONNECTICUT.

ELASTIC CUFF LINK.

Application filed September 10, 1925. Serial No. 55,512.

To all whom it may concern:

Be it known that I, WALTER E. LENA, a citizen of the United States, and a resident of Waterbury, county of New Haven, and 5 State of Connecticut, have invented certain new and useful Improvements in Elastic Cuff Links, of which the following is a specification.

This invention relates to cuff links, and 10 more particularly to elastic cuff links in which the elastic member is anchored by an improved form of clasp.

One object of this invention is to provide 15 an elastic attachment clasp of the above nature which cannot tear or otherwise injure the elastic member.

A further object is to provide a device of 20 the above nature in which the portion of the elastic member within the clasp will be clamped in stretched condition, thus eliminating all rubbing contact with the metal parts of the cuff link.

A further object is to provide a device of 25 the above nature which will be simple in construction, inexpensive to manufacture, easy to manipulate, ornamental in appearance, and very efficient and durable in use.

With these and other objects in view, there 30 have been illustrated on the accompanying drawings two forms in which the invention may be conveniently embodied in practice.

Fig. 1 represents a plan view of a metal blank from which the attachment clasp is 35 constructed.

Fig. 2 is a perspective view of the clasp after the end tabs have been bent up from the body of the clasp.

Fig. 3 is a perspective view of a modified 40 form of clasp having its tabs bent up from the body in a somewhat different manner.

Fig. 4 is a perspective view of one end of 45 the elastic member and showing the anchoring clasp connected thereto.

Fig. 5 is a perspective view of the elastic 50 member together with both of its clasps, and showing the back plates of the two cuff buttons assembled thereon.

Fig. 6 is a side sectional view of a completely assembled cuff link.

Fig. 7 is a perspective view of a cuff 55 upon which one of the improved cuff links has been attached.

Previous forms of elastic cuff links have 60 proven unsatisfactory in use on account of the fact that the ends of the elastic cord were not clamped securely in the buttons,

but had a tendency to rub against the metal parts until the cord snapped off. There was also a tendency for the loose interior of the cord to slip out of its covering, in either 60 case allowing the links to become disconnected.

According to the present invention, the above and other disadvantages have been avoided. This has been accomplished by 65 providing an improved form of clasp for anchoring the ends of the elastic cord within the buttons connected thereto. The use of these improved anchoring clasps positively prevents slippage and breakage of the cord 70 and permits a cord of more flexible and attractive material to be used.

Referring now to the drawings in which like reference numerals denote the corresponding parts throughout the several 75 views, the cuff link herein disclosed comprises an elastic cord 10, each end of which is connected to a pair of buttons, generally indicated by the numerals 11.

Each of the buttons 11 consists of a cup-shaped shell member 12 and a back plate 13, the latter being secured in place by a flange 14 integral with the rim of the shell member 12, as clearly shown in Fig. 6. Each of the back plates 13 has a slot 15 adapted to 80 fit over the cord 10, and both of said plates are slipped over the cord before attaching the clasps and buttons thereto.

In order to anchor the elastic cord in the buttons, provision is made of a pair of anchoring clasps 17, one of which is adapted to be secured to each end of said cord. The clasps 17 are preferably constructed from rectangular blanks of strip brass, one such blank being shown in Fig. 1. Each of said 90 blanks has a central body member 17^a and a pair of slits 18 cut into its opposite ends to form a series of tabs 19, 20, 21, and 22.

The process of attaching one of the clasps 17 to the end of the elastic cord will now 100 be described. The extremity of said cord will first be laid on one side of the body member 17^a and will be clamped thereto by bending over two of the tabs, such as the tabs 19 and 20. The cord will then be looped around the bent-over tabs 19 and 20 and pulled around the side of the body member 17^a, after which it will be laid in stretched condition upon the other side of said body member. The other two tabs 21 and 22 will 105 be then bent down to clamp the cord.

As will be clear from this construction,

each extremity of the cord will be held by a double clamping action and the tighter the pull on the cord the greater will be the said clamping action. After the clasps have been attached to both ends of the cord, the back plates 13 will be moved into contact with said clasps. The buttons of the cuff link will then be assembled in any suitable machine, such as a press, during which 10 operation the flanges 14 will be forced down upon the plates 13.

The appearance of the cuff link when in use is illustrated in Fig. 7, the buttons 11 thereof being shown engaging opposite sides 15 of a cuff 16.

It will be understood that while this invention is especially designed for cuff links, it is equally applicable to collar tip connectors, shoe strings, hat strings, and the like.

20 One advantage of this invention is that the ends of the elastic cord are held immovable in stretched condition, and consequently all rubbing action, such as was present in previous devices of this general nature, will 25 be eliminated.

While there have been disclosed in this specification two forms in which the invention may be embodied, it is to be understood that these forms are shown for the purpose 30 of illustration only, and that the invention is not to be limited to the specific disclosures but may be modified and embodied in various other forms without departing from its spirit: In short, the invention includes 35 all the modifications and embodiments coming within the scope of the following claims.

Having thus fully described the invention, what is claimed as new and for which 40 it is desired to secure Letters Patent, is:

1. In an elastic cuff link, an elastic cord formed of woven fabric, a pair of hollow cuff buttons at the ends of said cord, and a pair of anchoring clamps formed separately 45 from said buttons and clamped upon the ends of said cord within said buttons.

2. In an elastic cuff link, an elastic cord, a pair of anchoring clasp secured to the 50 ends of said cord, each of said clasp being enclosed within a shell member and a back- 55 ing member, each of said clasp having a central body member, and means extending from opposite sides of said body member for clamping about said cord.

3. In an elastic cuff link, an elastic cord, a pair of anchoring clasp secured to the 55 ends of said cord, each of said clasp being enclosed within a shell member and a back-

ing member, each of said clasp having a central body member, and tabs extending 60 from opposite sides of said body member for clamping about said cord.

4. A clasp for anchoring the end of a cord in a button, comprising a body member, said body member having tabs extending in opposite directions therefrom, said tabs being adapted to be bent over to clamp said cord to said body member, said cord being looped around both ends of said body member and being clamped by both sets of tabs. 70

5. A clasp for anchoring the end of a cord in a button or the like, comprising a body member of strip metal, said body member having clamping means extending from opposite sides thereof, said cord being looped around said clasp to lie in contact with both sides of said body member. 75

6. In an elastic cuff link, an elastic cord of woven fabric, a pair of hollow cuff buttons at the ends of said cord, and a pair of anchoring clamps formed separately from 80 said buttons and clamped upon the ends of said cord within said buttons, each of said cuff buttons comprising a shell member and a backing member. 85

7. In an elastic cuff link, an elastic cord of woven fabric, a pair of hollow cuff buttons at the ends of said cord, and a pair of anchoring members formed separately from 90 said buttons and clamped upon the ends of said cord within said buttons.

8. A clasp for anchoring the end of a cord in a button or the like, comprising a body member, means extending from opposite sides of said body member for clamping said 95 cord to said body member, said cord being adapted to pass through the back of a button.

9. In a clasp for anchoring the end of an elastic cord in a button or the like, a body 100 member, means for clamping said cord against opposite sides of said body member, said cord being held immovable in stretched condition in said clasp, whereby all rubbing action will be prevented. 105

10. In a clasp for anchoring the end of an elastic cord, a body member, said body member having tabs extending from opposite sides thereof, said cord being looped around one end of said body member and clamped to said body member by both sets of tabs. 110

In testimony whereof, I have affixed my signature to this specification.

WALTER E. LENA.
